UNITED STATES PATENT OFFICE.

HERMAN B. THURSTON, OF CLEVELAND HEIGHTS, OHIO.

LOW-WATER ALARM.

Application filed March 19, 1925. Serial No. 16,627.

This invention relates to low water alarms for steam boilers and the object is to provide an alarm which will be sure of operation while there is still a safe amount of water over the crown sheet. The alarm herein shown is of the type wherein a conduit connection is made between the steam space of the boiler and an alarm device located exteriorly of the boiler, the conduit being normally closed by a fusible plug connected by heat conducting means with a portion of the fire box and located at the point where the water in the boiler is said to be at a dangerous level. It is desirable to place such a plug within a short distance of the uppermost portion of the crown sheet of the boiler so that when the water level reaches and passes the region of the plug, the steam above the water level will not have sufficient cooling effect on the metal surrounding the plug to prevent the heat conducted from the fire box from melting the plug and opening the passage to the signal.

However, I have found that in the use of such an alarm the water may reach a dangerously low level while the position of the boiler is substantially horizontal and then for instance, by reason of the sudden stopping of a locomotive carrying the boiler or of such a locomotive reaching the end of a level stretch of track and starting down hill the water level may fall so far below the crown sheet that, although the alarm does sound, the water cannot be raised to cover the crown sheet before the sheet has become weakened by overheating to a degree which will make it unable to withstand the boiler pressure. An accident resulting from such a condition would result in serious damage to the boiler and would very likely endanger the lives of the crew.

An obvious remedy for this would seem to be to elevate the position of the fusible plug so that it would respond in time before the water level has reached the crown sheet but I have found by extensive and repeated experiments that the likelihood of the fusible plug, such as heretofore used, being fused at the right time is diminished by reason of the distance which the heat from the fire box will have to travel to the plug, if it be too remote from the crown sheet.

The water in contact with the alarm cage draws heat away from the means conducting heat from the fire box to the fusible plug,

and it frequently happens that the level of the water may be well below the crown sheet before the fusible plug melts causing the alarm to sound. As a result of these conditions determined by experiments, I have devised a means for preventing water slightly above the level of the crown sheet, from nullifying the effect of the heat passage from the fire box to the fusible plug, thereby both controlling and more accurately governing the time at which the fusible plug will melt with relation to the water level above the crown sheet. The means includes a closed insulating jacket surrounding certain of the parts of the alarm associated with the fusible plug and arranged to insulate the heat conducting path from the fire box to the plug. It is to be understood that my insulating scheme is intended for use with any type of alarm located within the boiler and employing a thermo-responsive element adapted to act by reason of heat conducted from the fire space to sound an alarm.

The details and operation of my invention will become more clear in connection with the description to follow which relates to the accompanying drawings. The essential novel characteristics will be summarized in the claims.

In the drawings Fig. 1 is a substantially central longitudinal section through a portion of the low water alarm embodying the preferred form of my invention showing the alarm attached to the roof and crown sheet of a boiler; Fig. 2 is a transverse section as indicated by the line 2-2 on Fig. 1.

Indicating the various parts of the apparatus by numerals, 1 designates a portion of the roof sheet of a boiler, 2 a similar section of the crown sheet. Access for the live steam to the alarm may include a combination packing fixture and casing member 5 in threaded engagement with the roof sheet at 6. The casing has a chamber 7 open at the bottom at 8 through which opening a tube 9 may extend into the chamber. The tube may be spaced apart from the sides of the opening and is shown as arranged to be separated from the upper end of the chamber whereby a continuous passage may be had from the steam space through the opening 8 into the top of the tube.

The tube communicates at its lower end with a plug cage 15 which in the type of alarm shown houses the thermo-responsive

element, in this case a fusible metal plug, the cage being arranged to be secured to the crown sheet as by the threads 16. In the upper portion of this cage is a series of openings 17 which admit the steam from the tube 9 into a pocket 18 in the cage. In this pocket the egress of steam is prevented by a plug 19 threaded at 20 into a central opening in the cage. The plug may be of any suitable form adapted to contain a slug of fusible material such as tin alloy shown at 22 filling the upper portion of a longitudinal opening 23 through the plug. The upper end of the opening is shown as entering a second chamber 24 in the cage, into which extends a pipe 25. The pipe may extend through the tube 9, packing 27, a packing gland 28 and nut 29, to a signal device such as a whistle 30 located exteriorly of the boiler. The whistle is shown in the drawings as supported partly by the pipe and partly by a supporting eye and bracket 32 and 33 respectively.

The lower end of the casing 15 is shown as closed by the plug 35 threaded at 36 in the casing and as provided with an extension 37 projecting downwardly into the fire box. The portion 37 is preferably provided with angular surfaces to facilitate its removal from the cage.

The advantages of such an arrangement of the parts of the alarm are set forth in my prior applications of which an example is Serial No. 726,711 filed July 18, 1924.

The means whereby I insure the timely operation of the alarm constitutes the primary feature of my invention. This means is preferably a heat insulating device consisting of a cylindrical casing 40 shown as surrounding the cage and extending over the adjacent enlarged portion of the tube 9. The ends of the casing may curve inwardly as shown at 41 and 42 to engage the wall of said cage and said tube respectively, to form an insulating space 45 between the water chamber and the cage 15. Any suitable means may be utilized for holding this insulating casing in place, such as welding, brazing or the like, about its upper and lower rims at the lines of engagement with the cage 15 and the tube 9 as indicated at 46 and 47.

I have found that the distance between the fusible plug and the crown sheet should be such that the plug will not melt when there is still water enough in the boiler to permit the safe operation of the locomotive. Likelihood of the premature fusing of the plug is prevented if the distance is substantially that indicated by the proportion shown in the drawings, yet the warning will be given in sufficient time to allow the operator to recover the water level before damage has resulted to the crown sheet.

As previously pointed out, without such

an insulating jacket any water at all around the cage draws heat from the conducting path leading to the fusible plug. Thus when the recession of the water is rapid, the time required for accumulating sufficient heat in the conducting means leading to the plug is such that the water level is well below the plug and perhaps the crown sheet is exposed before the heat melts the fusible plug.

By the use of my invention however, heat begins to accumulate from the fire box in the plug 37 and the surrounding cage 15 as soon as the general level of the water is slightly below the top of the casing 40 by which the water is prevented from having any direct cooling effect on the cage. Therefore by the time the water has dropped to about the level even with the fusible plug 22, this accumulated heat will be sufficient to melt the plug. Then the passage which includes the chamber 5, the conduit 9 and the pipe 25 will be opened and the steam will force the now melted particles of the plug outward along the pipe 25 and sound the alarm.

It is to be understood that variations in the general design may be made without departing from the spirit of my invention. It will be seen that I have provided a low water alarm which will function to open the passage and allow the alarm to operate at the desired time, irrespective of surging of the water in the boiler and in plenty of time to prevent any damage to the crown sheet, and consequent danger to the lives of persons in the vicinity of the boiler.

Having thus described my invention, I claim:

1. In a low water alarm, a member having a passage adapted to communicate with the steam space at one end and with an alarm device at the other, plug carrying means within the boiler and located adjacent the crown sheet, and a fusible plug carried by said means and normally interrupting said passage, means whereby heat is conducted from the fire space to said plug and an insulating means surrounding a portion of the plug carrying means and arranged to prevent water contact with said plug carrying means.

2. The combination with a boiler structure including a fire box and a crown sheet, of a low water alarm, said alarm comprising a signal, a member having a plurality of passages adapted to lead steam from the boiler to the signal, a fusible plug normally closing communication between said passages, metallic means secured to the crown sheet having a portion thereof exposed to the heat of the fire box for conducting heat therefrom to the plug, a jacket surrounding said means for preventing water contacting with the heat conducting means, the jacket

preventing contact from a point adjacent the crown sheet to a point materially above the fusible plug.

3. The combination with a boiler structure including a fire box and a crown sheet, of a low water alarm, said alarm comprising a signal, a member having a plurality of passages adapted to lead steam from the boiler to the signal, a fusible plug normally closing communication between said passages, a heat conducting member for housing the plug secured to the crown sheet, and means including a heat insulating member surrounding the plug portion of the heat conducting member whereby when the water level drops below the top of the jacket sufficient heat may be conducted from the fire box to melt the plug.

4. The combination with a boiler structure including a fire box and a crown sheet, of a low water alarm, said alarm comprising a signal, a member having a plurality of passages adapted to lead steam from the boiler to the signal, a fusible plug normally closing communication between said passages, heat conducting means extending between the crown sheet of the boiler and the plug and an insulating jacket surrounding a portion of said heat conducting means in the zone of the plug, whereby when the water in the boiler drops below the top of the jacket, heat conducted from the fire space accumulates rapidly in the region of the plug causing it to be fused.

5. A low water alarm for a boiler having a roof sheet and a crown sheet, the alarm comprising in combination a signal, a member having a passage leading from within the boiler to the signal, a fusible plug normally closing said passage, means secured to the crown sheet for carrying said plug, having a heat conducting portion extending within the fire box for leading heat therefrom to the plug, a surrounding insulating jacket for preventing contact of the water in the boiler with said conducting means said jacket extending from a point near the crown sheet to a point above the plug, whereby when the mean level of the receding water in the boiler reaches the last named point, the water is prevented from withdrawing heat from the conducting member.

6. A low water alarm comprising a casing member adapted to be secured to the roof sheet of a boiler, a member having a passage communicating with the casing for conducting steam therefrom, means normally closing the passage including a fusible metallic plug, a plug cage supporting said closing means having a portion thereof in communication with the fire space of the boiler, a passage leading from the plug to the exterior of the boiler adapted to communicate with a signal device and a heat insulating casing spaced apart from the plug cage in

the zone of the plug and contacting therewith above and below the zone of the plug whereby water in the boiler is maintained out of contact with the cage at this point.

7. The combination with a boiler structure including a fire box and a crown sheet, of a low water alarm, said alarm comprising a signal, a member having a plurality of passages adapted to lead steam from the boiler to the signal, a fusible plug normally closing communication between said passages, means in threaded engagement with the crown sheet forming a part of said passages and carrying said fusible plug, means within and in threaded engagement with said last named means for conducting heat from the fire box to the plug and an insulating means comprising a jacket substantially preventing water contact with the plug mounting and said conducting means.

8. The combination with a boiler structure including a fire box and a crown sheet, of a low water alarm, said alarm comprising a signal, a member having a plurality of passages adapted to lead steam from the boiler to the signal, a fusible plug normally closing communication between said passages, means carried by the crown sheet and forming a part of said passages for carrying said fusible plug, means within said last named means for conducting heat from the fire box to the plug and an insulating means surrounding the last two mentioned means comprising a water tight jacket separated from the plug carrying means in the zone of the plug and contacting therewith above and below this zone.

9. In a low water alarm, a metallic container located within a boiler and secured to the crown sheet thereof, a thermo-responsive element carried thereby, means affording heat conductivity from the fire space of the boiler to the container, an alarm externally of the boiler arranged to be actuated under the control of said element, and insulating means in spaced relation to the container and embracing the same, for preventing water contact with the embraced portion of the container.

10. In a low water alarm, a container located within a boiler, a thermo-responsive element supported thereby, means extending into the fire space and in threaded engagement with the container above the crown sheet of the boiler for providing direct heat conductivity from the fire space to the element, an alarm externally of the boiler arranged to be actuated consequent upon the fusing of the element, and insulating means in spaced relation to the container, surrounding the same and sealed against the entrance of fluid in the boiler whereby such fluid is prevented from contacting with the container.

11. In a low water alarm, a hollow con-

- tainer member located within the steam and water chamber of a boiler, a thermo-responsive element supported thereby, a signal device located externally of the boiler and arranged to be actuated under control of said element, a closure member for the container extending into the fire space of the boiler and being in intimate contact with the container above the crown sheet of the boiler
- 10 for providing direct heat conductivity to the element from the fire space, and an insulating means comprising a jacket embracing a portion of the first named member and the said element, the jacket being sealed
- 15 about the hollow member to prevent the steam and water from contacting with the embraced portion.
12. In a low water alarm, a hollow container located within a boiler, a thermo-responsive element carried by the container and removable therefrom from within the fire box of the boiler, means including a closure member for the container in spaced relation to the crown sheet and extending therethrough for conducting heat from the fire space to the element, an alarm device externally of the boiler arranged to be actu-
- 20
- 25

ated consequent upon sufficient heating of the element, and insulating means surrounding and spaced apart from the container for a distance along the same.

13. In a low water alarm for a boiler, a cage located within the boiler, a thermo-responsive element within the cage and located entirely above the crown sheet of the boiler, an alarm externally of the boiler arranged to be actuated under control of the element and a jacket surrounding and spaced apart from the cage and secured thereto in enveloping relation for preventing direct contact of water or steam in the boiler with the cage.

14. In a low water alarm for a boiler, a cage within the boiler, a thermo-responsive element within the cage, an alarm external of the boiler arranged to be actuated under control of the said element and a tubular insulating jacket embracing the cage, spaced apart therefrom intermediately of its ends and in sealed relation thereto at its ends.

In testimony whereof, I hereunto affix my signature.

HERMAN B. THURSTON.
